UNITED STATES PATENT OFFICE.

PAUL FRANKOIS, OF NANTICOKE, PENNSYLVANIA.

PHOTOGRAPHIC ENLARGING APPARATUS.

Application filed June 15, 1922. Serial No. 568,535.

To all whom it may concern:

Be it known that I, PAUL FRANKOIS, a citizen of the United States, residing at Nanticoke, in the county of Luzerne and State of Pennsylvania, have invented certain new and useful Improvements in Photographic Enlarging Apparatus; and I do declare the following to be a full, clear, and exact description of the invention, such as will enable others skilled in the art to which it appertains to make and use the same.

The present invention relates to an improved photographic enlarging apparatus by which enlarged photographic prints may be made from photographic negatives.

The apparatus has many improved features of construction, but its principal improved feature is a mechanism by which the lens is automatically focused as the device is adjusted to produce an enlargement of the desired size. With the apparatus enlarged prints of various sizes may be made from negatives of various sizes, but in adjusting the apparatus to produce an enlargement of a desired size, the lens is automatically focused by an improved simply constructed mechanism.

The apparatus is constructed so that very little floor space in a dark room would be occupied in setting it up, and so that when not in use, it can be partly folded and partly moved to an out-of-the-way position. This construction forms another important feature of the invention.

The part of the apparatus which carries the light, negative and lens and which is adjustable toward and away from the holder for the sensitized paper on which the enlargement is made, has a vertical sliding adjustment so that in using the apparatus, very little if any, centering of the image upon the sensitized paper would be necessary. Furthermore, the apparatus is so evenly balanced that the parts thereof carrying the light, negative and lens may be quickly and easily adjusted to produce the desired size enlargements. The even balancing of the part of the apparatus which carries the light, negative and lens is such that when this part is adjusted to the desired position, it will maintain such position.

The apparatus is provided with means by which a tinted border may be produced around the enlarged picture at the same time the sensitized paper is exposed by the en-

larged image thrown thereon. This improved means is such that tinted borders of varying degrees of sharpness and of varying shades or densities may be produced.

The apparatus is of comparatively simple construction, is easy to operate and is thoroughly efficient and reliable in operation. Its novelty consists in the various features of construction, and the combination and arrangement of parts which are herein-after described and claimed and shown in the accompanying drawings which form a part of this specification.

In the accompanying drawings: 70

Fig. 1 is a side elevation of a portion of an apparatus embodying the principles of the present invention.

Fig. 2 is a front elevation of the supporting standard, illustrating the slide to which the bracket members for the light, negative and the lens is fixed, partly in elevation and partly in section.

Fig. 3 is a horizontal sectional view of a portion of the apparatus taken substantially on the plane indicated by the line 3—3 of Fig. 1.

Figs. 4 and 5 are vertical sectional views of portions of the apparatus taken substantially on the planes indicated by the lines 4—4 and 5—5 respectively of Fig. 1.

Fig. 6 is a bottom view of the frame which holds the mask for producing a tinted border upon an enlargement and for holding the negative to be enlarged.

Fig. 7 is a top view of the frame shown in Fig. 6.

Figs. 8 and 9 are respectively longitudinal and transverse sectional views of the frame shown in Figs. 6 and 7.

Figs. 10 and 11 are top views of a frame carrying reflectors which are used in varying the density or shade of the tinted border produced upon the enlargement, showing the reflectors in different adjustments; and 100

Fig. 12 is a longitudinal sectional view of the frame illustrated in Figs. 10 and 11.

In the illustrated embodiment of the invention, the numeral 1 designates an upright supporting standard upon which the various parts of the apparatus are mounted. The standard 1 is intended to be placed in a dark room with its back against a wall and is intended to be anchored to the wall by any suitable means. It preferably rises from the floor of the room to a point above the average height of a person. It may be

constructed in numerous ways, but it is preferably hollow, of box-like construction, and has its upper end open.

At the front of the standard 1 are secured a pair of opposed upright parallel rails 2 and 3. These rails 2 and 3 form the guides for a vertically movable slide 4, to which is fixed a forwardly projecting bracket frame 5. At the upper end of the standard 1, there is revolubly mounted a pulley 6 over which passes a cable 7 secured at one end to the bracket frame 5 and having a counterweight 8 suspended from its other end and disposed for vertical movement in the hollow portion of the standard 1. Pivoted to the frame 5 is a handle 8' by which said frame may be raised and lowered.

The numeral 9 represents a table for supporting the sensitized paper on which the enlargement is made. By preference, this table 9 is hinged at its rear end to the standard 1 at a point a short distance above the floor of the dark room and is provided with a foldable leg 10 for supporting its front end. By this construction, when the apparatus is not in use, the table 9 may be swung upwardly upon its hinge alongside the standard 1 and the leg 10 may then be swung downwardly so that the entire table may be out of the way when not in use.

Secured to the front of the bracket frame 5 in any suitable manner is the box 11 of an enlarging camera. The upper portion of the box 11 supports an illuminating device consisting of an electric light bulb 12 and a reflector 13. To the lower end of the box 11 is secured one end of the bellows 14 of the camera. The other end of the bellows 14 is fastened to the front of the camera which carries the lens 16.

The front 15 of the camera is slidably connected to a slide 17, which in turn is slidably mounted between a pair of guide rails 18 and 19 which are fixed to the front of the supporting bracket frame 5. The front 15 of the camera may be adjusted along the slide 17 by means of an adjusting screw 20.

Secured to the bracket frame 5 in any suitable manner is a supporting plate 21 upon which is revolubly mounted a worm gear 22. The worm gear 22 meshes with a worm 23 fixed upon one end of a shaft 24, the other end of which carries the pinion 25. The shaft 24 is mounted in a bearing 26 carried by the plate 21 and a bearing 27 carried by the slide 4. Meshing with the pinion 25 is a pinion 28 mounted upon a stub shaft 29 carried by the slide 4. The pinion 28 meshes with a rack 30 which is secured to the hereinbefore described rail 3.

Mounted upon the shaft upon which the worm wheel 22 is mounted and coupled to the worm wheel 22 in such a manner as to

turn therewith is a cam 31. The cam 31 is by preference of the crescent-shape type and engages an arm 32 which extends laterally from one side of a lever 33, one end of which is pivoted at 34 to the plate 21 and the other end of which is adjustably secured to one end of a link 35. The other end of the link 35 is pivotally connected to a lug 36 which is carried by the slide 17.

The cam 31 is mounted upon the shaft of the worm wheel 22 in such a manner that it can be removed therefrom and replaced by a similar cam of a size for use in connection with a lens having a different focal length than the lens 16.

Mounted in any suitable manner in the box 11 of the camera is a piece of ground glass 37, the purpose of which is to diffuse the light emanated by the electric bulb 12 before it reaches the photographic negative.

The negative holder comprises an outer frame 38 which is mounted in the box 11 of the camera in such a manner that it can be removed therefrom. The outer frame 38 carries an inner frame 39, which in turn carries a plate 40 of transparent glass. The glass plate 40 is mounted in the inner frame 39 in such a manner that it can be removed therefrom. The negative from which an enlarged photographic print is to be obtained is to be placed in contact with the glass plate 40 and held in place by means of spring clips 41. In Figs. 7, 8 and 9 of the drawings, a negative N is shown in place upon the plate 40.

In Figs. 6, 8 and 9 of the drawings, the numeral 42 represents a frame which carries a glass plate 43. This frame 42 is mounted upon the lower side of the frame 39 for adjustment toward and away from the same. The means by which the frame 42 is mounted upon the lower side of the frame 39 consists of a pair of springs 44 which are secured at their intermediate portions to the frame 39 and which have their ends hooked around pins 45 carried by the frame 42. In this manner, the frame 42 may yield away from the frame 39.

Pivottally mounted between its ends upon the lower side of the frame 39 is a lever 46. The ends of this lever are secured to bars 47 which are slidably mounted upon the lower side of the frame 39 and which carry inclined or wedge-shaped shoulders 48. The shoulders 48 engage pins 49 carried by the frame 42 in such a manner that when the bars 47 are shifted longitudinally, the frame 42 will be moved toward or away from the frame 39. In order to rock the lever upon its pivot, the frame 38 carries an adjusting screw 50. This screw 50 is threaded through a lug 51 carried by the lever 46 so that when the screw is turned, it will pull or push the lever 46.

The frame 42 is intended to carry a mask

by which a tinted border upon the enlargement is produced. In Figs. 6, 8 and 9 of the drawings, such a mask is shown and indicated by the letter M. The mask M when used 5 is placed in contact with the lower side of the glass plate 43 and held in this position by means of spring clips 52, secured at one of their ends to the frame 42. The mask of course has a cutout portion designed to be 10 placed over the portion of the negative desired to be enlarged. The lower side of this cutout portion of the mask is provided with a white border B while the remaining portion is preferably black or of a very dark 15 color.

Mounted in the box 11 of the camera beneath the frame 38 which carries the negative holding frame and the mask holding frame is a frame 53 upon which four reflecting blades 54, 55, 56 and 57 are mounted. The frame 53 is preferably removable from the box 11 and is preferably of rectangular shape. The blades 54 and 55 are longer than the blades 56 and 57 and are 20 mounted at their outer edges upon shafts 58 and 59 which extend longitudinally along the side edges of the frame 53. One of the ends of the shafts 58 and 59 are provided with crank arms 60 and 61 respectively. 25 The blades 56 and 57 are mounted upon transversely extending shafts 62 and 63, but the inner ends of these blades 56 and 57 rest upon the blades 54 and 55 so that the blades 56 and 57 will be moved or adjusted 30 by the blades 54 and 55.

Mounted upon one end of the frame 53 is a turnable knob 64. The stem of this knob 64 extends into the interior part of the frame and carries an arm 65. The arm 65 is 40 secured at its intermediate portion to the stem of the knob 64 and its ends are connected by links 66 and 67 to the swinging ends of the crank arms 60 and 61 respectively. With this construction, whenever the knob 45 64 is turned, the arm 65 will be turned and the links 66 and 67 will be pulled or pushed so as to swing the crank arms 60 and 61 and the blades 54 and 55 and also the blades 56 and 57. Thus, the opening 68 defined 50 by the inner edges of the blades 54, 55, 56 and 57 may be varied in size.

In using the apparatus, a negative such as N should be placed upon the glass plate 40 and held in position thereon by means of the spring clips 41. The circuit to the electric light bulb 12 should then be turned on so as to light the bulb and the bracket frame 5 should be raised or lowered by hand until the image projected through the negative and the lens 16 of the camera upon the table 9 is of the size desired for the enlargement to be made. The counterweight 8 is of proper weight to exactly balance the parts of the apparatus which are carried by the frame 5 so that when the latter has been moved

to the desired position, it will stay in such position without any special locking means.

As the bracket frame 5 is raised or lowered to project an image of the desired size upon the table 9, the lens 16 of the camera 70 will be automatically focused. This automatic focusing of the lens is brought about in the following manner:

In the first place, when the slide 4 is raised or lowered, the pinion 28 which meshes with the stationary rack 30 will be turned and in turning, it will turn the pinion 25, the shaft 24 and the worm 23. The turning movement of the worm 23 will impart a slow turning movement to the worm wheel 22 and 80 a similar movement will be imparted to the cam 31. The cam 31 engaging the arm 32 carried by the lever 33 will swing the lever, and the latter being coupled to the slide 17 by means of the link 35 and the lug 36 will 85 cause the slide 17 to be moved vertically upon the rails 18 and 19. Since the front 15 of the camera carrying the lens 16 is fastened to the slide 17, whenever the slide 17 is moved a corresponding movement will be 90 imparted to the lens 16.

The pinions 25, 28, the worm 23, the worm wheel 22, the cam 31 and the lever 33 are of mathematically computed sizes so that exactly the proper amount of movement will be 95 imparted to the lens 16 to automatically maintain it focused as the camera is raised or lowered.

Of course, after the negative has been placed in the negative holder and the camera has been adjusted so that an enlargement of the proper size will be made, a sheet of sensitized paper should be placed upon the table 9 and the light 12 should be turned on so as to expose the sensitized paper for 105 the proper length of time.

If it is desired to produce a tinted border upon the enlargement, then before the sensitized paper is exposed, a mask M should be placed in contact with the glass plate 43 carried by the frame 42 and held in contact with the glass plate by means of the spring clips 52. By turning the screw 50, the frame 42 may be adjusted toward and away from the frame 39, and by this means the degree 110 115 of softness of the tinted border produced on the enlargement can be varied.

The density or shade of the tinted border produced upon the enlargement can also be varied. This, however, is done by turning 120 the knob 64 so as to adjust the reflectors 54, 55, 56 and 57. These reflectors reflect the diffused light which passes around the edges of the negative back onto the border B of the mask M, and when the border B is illuminated in this manner, an image of it will be projected upon the sensitized paper to produce the tinted border thereon. It is therefore obvious that the intensity of the light forming the image of the border can 125 130

be varied by varying the position of the reflectors.

Although the apparatus is provided with an automatic focusing mechanism for the lens, yet if desired, the lens can be focused by hand by operating the adjusting screw 20. This screw 20 is, however, primarily intended to adjust the lens 16 after the link 35 has been coupled to the lever 33. An adjustment of this nature may also be obtained by adjusting the upper end of the link 35 upon the swinging end of the lever 33. When the adjusting screw 20 is once adjusted, it is not necessary to alter its adjustment unless it should be desired to focus the lens by hand.

Where it is desired to use the apparatus for lenses of different focal lengths, a special cam 31 should be provided for each lens. The cam 31 is therefore removable and can be replaced by a similar cam suited for whatever lens is substituted for the lens 16.

From the foregoing description, taken in connection with the accompanying drawings, the construction, use and operation of the apparatus will be understood without further description.

It is apparent that numerous changes in form, proportion and in the various details of construction may be made without departing from the spirit and principle of the invention, and hence it is to be understood that changes of this nature may be made within the meaning and scope of the appended claims.

1. claim:

1. A photographic enlarging apparatus comprising a supporting member, a sensitized paper holder, an illuminating device, 40 negative holder and lens mounted for sliding adjustment upon said supporting member, said lens being movable toward and away from said negative holder, a swinging lever coupled to the mounting for the lens in such a manner as to move the lens toward and away from the negative holder, a cam for swinging said lever to cause it to move the lens toward and away from the negative holder, and gearing interposed between said supporting member and said cam for imparting movement to said cam as said illuminating device, negative holder and lens as a unit are moved upon said supporting member.

2. A photographic enlarging apparatus comprising an upright standard, a bracket frame slidably mounted for vertical movement upon said standard, a unit consisting of an illuminating device, negative holder and lens carried by said bracket frame, said lens being movable toward and away from said negative holder, a lever pivoted upon said bracket frame and operatively connected to the mounting for said lens in such

a manner as to move said lens toward and away from said negative holder, a cam rotatably mounted upon said bracket frame and engaging said lever so as to move it and cause said lens to be moved toward and away from said negative holder, and gearing interposed between said standard and said cam for driving the latter as said bracket frame is adjusted vertically upon said standard. 70

3. A photographic enlarging apparatus 75 comprising an upright supporting standard, a bracket frame slidably mounted for vertical adjustment upon said standard, an illuminating device, negative holder and lens constructed as a unit and carried by said frame, said lens being movable toward and away from said negative holder, a lever pivotally mounted upon said frame and operatively connected with the mounting for said lens in such a manner as to move the 80 lens toward and away from said negative holder, a cam rotatably mounted upon said frame and engaging said lever in such a manner as to swing it and cause said lens to be moved toward and away from said negative holder, a rack fixed upon said standard, a pinion carried by said frame and meshing with said rack in such a manner that it will be rotated as said frame is adjusted vertically upon said standard, and gearing interposed between said pinion and said cam for imparting movement from said pinion to said cam. 85

4. A photographic enlarging apparatus 90 comprising an upright supporting standard, a bracket frame slidably mounted for vertical adjustment upon said standard, an illuminating device, a negative holder and a lens constructed as a unit and carried by said frame, said lens being movable toward and away from said negative holder, a lever pivoted upon said frame, an adjustable connection between said lever and the mounting for said lens, a cam mounted upon said frame for swinging said lever, and driving 100 means for said cam, said driving means being geared to said standard in such a manner as to rotate said cam as said frame is adjusted vertically upon said standard. 105

5. In a photographic enlarging apparatus, the combination of a negative holding frame, a frame for holding a mask for producing a tinted border upon an enlargement, resilient means for securing the second frame to the first frame in such a manner as to permit the second frame to be moved toward and away from the first frame, a pair of bars slidably mounted upon the first frame, cooperating cam means carried by said bars and the second frame for moving the latter toward and away from the first frame as said bars are slid, a lever pivoted to the first frame and coupled to 110 115 120 125

said bars so as to slide the latter longitudinally, and means for shifting said lever upon its pivot.

6. In a photographic enlarging apparatus, the combination of an illuminating device, a negative holder, a lens on the opposite side of said negative holder from said illuminating device, a frame for holding a mask for producing a tinted border upon an enlargement disposed between said negative holder and said lens, a mask mounted in said frame and having a light colored border surrounding the opening

therein, a plurality of swinging reflector blades disposed between said frame and said lens and being adapted to reflect the light which passes around the negative placed in said negative holder back onto the light colored border of said mask, the inner edges of said blades defining an opening, and means for adjusting the position of said blades so as to vary the size of said opening.

In testimony whereof I have hereunto affixed my signature.

PAUL FRANKOIS.
